FranceApplication June 5, 1936, Serial No. 83,739
In France July 3, 1935

2 Claims. (Cl. 185—11)

The present invention relates to an electro-mechanical device for periodic winding, adapted to be employed, in particular, for winding large or small clocks or similar movements, or for driving at definite intervals, during a predetermined length of time, a controlling or signalling mechanism.

One feature of the invention consists in a device for starting the winding or driving system at definite intervals, this starting being effected by the action of one or more pins rigidly connected to a member driven by the motion of the clock or movement, the said pin or pins acting on a lever, for starting and stopping the winding operation, which displaces a pawl, the axis of which is rigidly connected to this lever, and brings it into engagement with the following tooth of a ratchet wheel. When the lever is released (by the pin, the displacement of which is continued during the operating period) and restored to its initial position by the action of a spring, the pawl causes a rotation of the ratchet wheel corresponding to the advancement of one tooth.

Another feature of the invention consists in the combination of a cam disc mounted on the same axis as the ratchet wheel, and a double-armed lever, the profile of the said cam disc being such that one of the extremities of the lever may be either in a raised position or in a lowered position, according to whether its extremity rests on a projection or in a recess; to each of these positions there corresponds a definite position of a pair of brushes, which are associated with the commutator of an electric motor and are rigidly connected to the second lever-arm (stopping or running of the motor).

A further feature of the invention consists in the combination of the above two mechanisms, which combination allows, by the operation of the starting lever, of effecting the displacement of the friction members which come into engagement with the commutator, and, consequently, of obtaining the starting of the electric motor.

A still further feature of the invention consists in that the brushes are brought into engagement with the commutator by a sliding movement of the said brushes on the commutator.

Another feature of the invention consists in the combination of a cylinder or barrel enclosing the normal driving spring of the movement, with the starting member of the winding system and a wheel for winding the spring, the said wheel being driven either by any mechanical coupling device or directly by the electric motor and, consequently, causing the tensioning of the spring

during the operation of the motor and having, moreover, one or more stopping pins, the action of which on the starting and stopping lever causes the stopping of the winding system after a definite period of operation, by the action of the levers and of the ratchet wheel and cam disc previously mentioned. A pin rigidly connected to the cylinder drives the normal mechanism of the clock or movement.

The invention will be better understood by reference to the following more detailed description, given by way of non-limiting example, of the construction of a clock having a periodic winding system conceived in accordance with the spirit of the invention, and to the attached figures, of which

Fig. 1 illustrates a complete rear view of the mechanism of the clock and of the periodic winding system. Only the members which are necessary for understanding the invention have been illustrated. Moreover, for the sake of clearness in the illustration, the rear plate supporting the members has been assumed to be removed.

Fig. 2 illustrates a sectional view of Fig. 1 along the line 4—4.

Fig. 3 is a front view of the assembly of the cylinder, starting member, winding wheel and driving wheel of the time mechanism.

Fig. 4 is a side view of the assembly of Fig. 3, the different members having been spaced in order to show their arrangement more clearly.

The operation of the periodic winding system will now be explained with reference to these figures.

It is seen that, in the position shown in the figures, the member 5 for starting the winding operation is engaged and driven by the pin 6 rigidly connected to the cylinder 7. The said pin 6 also entrains the toothed wheel 8 in gear with the usual clock mechanism, the details of which have not been illustrated. In this manner, therefore, the normal driving of the clock mechanism is obtained by the action of a spring 9 within or otherwise associated with the cylinder or barrel 7, which drives the mechanism 45 through the pin 6, as has just been explained. The pin 6 will therefore effect a rotating movement about the axis of the cylinder in the direction indicated by the arrow in Fig. 1 (anticlockwise as viewed in the figure). In the example illustrated, it has been assumed that the said pin travels a complete revolution in one hour.

The winding member 5, which can rotate freely about its axis, has two diametrically-opposed pins 55

9 and 10. This arrangement of the pins has been adopted in order to obtain winding every half hour. As a result of the member 5 being entrained by the pin 6, one of the pins 9, 10 will engage every half hour with the starting and stopping lever 11.

Assume, as has been illustrated in Fig. 1, that the pin 9 engages the extremity of the lever 11. When the member 5 is further entrained by the pin 6, the pin 9 will displace the lever 11, which pivots about the axis 12 and carries along the pawl 13, the axis 14 of which is rigidly connected to the said lever 11. When the pin 9 has caused a certain displacement of the lever 11, the pawl 13 leaves the tooth of the ratchet wheel 15 on which it rested, and falls into the following tooth. Shortly after this action, the pin 9, continuing its rotary movement, releases the lever 11 which, under the action of the spring 21, returns to its initial position. During its return movement, the lever 11 carries along the pawl 13 which acts on the ratchet wheel 15, causing an anti-clockwise rotation of the said wheel corresponding to the advancement of one tooth.

Mounted rigidly on the same axis as the ratchet wheel 15 is a cam disc 16, on which bears the extremity of the arm 17 of a double-armed lever 17, 18 fulcrumed at 20. At the extremity of the second arm 18 is mounted an insulating member 19 supporting the two brushes 22 and 23 associated with the commutator 24 of the rotor 47 of an electric motor. As shown in Figs. 1 and 2 the working ends of the brushes are L-shaped in cross-section and are arranged so that one edge 35 of the L is adapted to engage the commutator. In the position illustrated in Fig. 1, the arm 17 bears against a projection on the cam disc 16 and only the brush 22 is in engagement with the commutator 24. The supply circuit of the 40 motor is open.

When, as has been explained, the ratchet wheel 15 advances by one tooth under the action of the pawl 13, the cam disc 16 is also thereby entrained which causes the extremity of the lever 45 arm 17 to enter a recess in the cam disc 16, under the action of the spring 46. This movement of the arm 17 raises the arm 18 pivotally about its axis 20, causing an upward displacement of the brushes 22 and 23, so that the brush 23 comes 50 into engagement with the commutator 24 and the rotor 47 of the electric motor is started by an electric current, from a supply battery or equivalent source, flowing through the flexible conductors 25 and 26 connected to the terminals 27 and 28. The inductive flux necessary for the 55 operation of the motor is furnished by the magnet 29 ending in the two pole-pieces 30 and 31.

It will be noted that the brushes are positioned by sliding them across the commutator, 60 which has a cleaning action, ensuring good electrical contact while preventing the introduction of additional contact resistances.

During its rotating movement, the rotor 47 drives the toothed wheel 38 rotatably mounted 65 on the shaft 50, for winding the spring 39, through the intermediate gear wheels 32 to 37. On the wheel 38 are mounted two diametrically opposed pins 40 and 41. After a period of winding of the spring corresponding to about half 70 an hour of operation of the clock, one of the pins 40, 41 engages the extremity of the lever 11 and causes the advancement of the ratchet wheel 15 by one tooth, in the same manner as has been described with reference to the pins 75 9, 10 for starting the winding system. How-

ever, in this case, the extremity of the arm 17, which rested in a recess in the cam disc 16, is lifted onto a projection by the movement of the said cam disc. Thus, in this case, the displacement of the arm 17 lowers the arm 18 to restore 5 the brushes to the position shown in the Fig. 1. The brush 23 is disengaged from the commutator 24 and the supply current to the motor is cut off.

However, owing to its inertia, the rotor 47 will 10 continue rotating for a short time after the current is interrupted, which will allow the pin 40 to disengage the extremity of the lever 11 so as not to interfere with the succeeding operation 15 of starting the winding. This additional rotation of the rotor will also assist in cleaning the commutator 24, after interruption of the current, by the action of the brush 22 which is still in engagement with the commutator.

The succeeding winding operation will be effected 20 under the action of the pin 10 of the member 5 and stopping will be effected by the action of the pin 41 of the winding wheel 38.

The winding wheel 38 is integral with a collar 38' (shown in Fig. 2 but omitted from Fig. 4 25 for the sake of clearness) to which is connected one end of the spring 39 arranged in the barrel 7. The other end of the spring 39 is connected to the barrel 7 so that unwinding of the spring 30 rotates the barrel to advance the pin 6.

The method of operation of the device is as follows:

The spring 39 drives the barrel 7 whereby the pin 6 is advanced to rotate the member 5 and also the toothed wheel 8 which drives the 35 clock mechanism. In this manner the member 5 rotates until either the pin 9 or 10 engages with the starting and stopping lever 11. Continued movement of the pin moves the lever 11 and the pawl 13 whereby the pawl engages 40 with the next following tooth of the ratchet wheel 15. Shortly thereafter the pin 9 disengages from the end of the lever 11 whereby the spring 21 returns this lever and the pawl 13 to their initial position thereby advancing the 45 ratchet wheel forward by one tooth.

The movement of the ratchet wheel simultaneously advances the cam disc 16, and the end of the arm 17 of the double armed lever 17, 18 moves into a recess in the cam disc, thereby permitting the spring 46 to rotate the double armed lever 17, 18 and move the brush 23 into engagement with the commutator to start the electric motor. Through the gear wheels 32 to 37 the winding wheel 38 is rotated to rewind the spring 55 39. In rotating the winding wheel 38, however, the pins 40, 41 are advanced and one of them (for example 40) also engages with the starting and stopping lever 11 to move the pawl 13 over the next following tooth of the ratchet 60 wheel 15. On continued movement of the pin 40 the lever 11 is released whereby the ratchet wheel is again advanced by one tooth. Simultaneously the cam disc 16 is advanced to move the lever arm 17 on to a projection thereof 65 whereby the brushes are moved away from the commutator to stop the rewinding motor.

It is obvious that the member 5 may be given any desired form and may be provided with any number of pins for effecting winding after a definite length of time, and the drive of the mechanism of the clock by a pin rigidly connected to the cylinder may be replaced by a toothed-wheel drive. In addition, it is possible to use fixed brushes which are constantly in engagement with 75

the commutator and to feed them through fixed contacts on which would be supported movable contacts actuated by the lever arm 18. These and other modifications are possible without departing from the ambit of the present invention.

5 The usual clock mechanism is protected from the action of the magnet 29 of the electric motor by a magnetic screen 44.

10 Although a specific embodiment of the invention has been described and illustrated, it will be clearly understood that many modifications and variations will be apparent to those skilled in the art which fall within the invention as defined in and by the appended claims.

15 We claim:—

1. A winding device for a clockwork mechanism comprising in combination a clockwork mechanism, a member driven by the clockwork mechanism, at least one pin connected to said member, 20 a starting and stopping lever operated by said pin, a ratchet wheel having teeth, a pawl associated with said ratchet wheel, means for displacing said pawl by the movement of said lever, said lever being released from said pin when the pawl is moved over a following tooth of the ratchet wheel, means for restoring the pawl to its initial position when released and thereby turning the ratchet wheel, a cam disc driven by said ratchet wheel, electrical contacts, means operated by 25 said cam disc when it has been stepped round

to close said electrical contacts, an electric motor controlled by said contacts, means for winding the clockwork mechanism by said electric motor, and means driven by said electric motor for operating the starting and stopping lever 5 again after a predetermined time, whereby said ratchet wheel and cam disc are again stepped round, and means for opening the electrical contacts when the cam disc is in this position.

2. A winding device for a clockwork mechanism 10 comprising in combination a clockwork mechanism, a member driven by the clockwork mechanism, a ratchet wheel having teeth, a pawl associated with said ratchet wheel, means for displacing said pawl by the movement of said member, 15 said pawl being released when it is moved over a following tooth of the ratchet wheel, means for restoring the pawl to its initial position when released and thereby turning the ratchet wheel, an electric motor, means operated when 20 the ratchet is stepped forward to start said electric motor, means for winding the clockwork mechanism by said electric motor, means driven by said electric motor for operating the pawl again after a predetermined time whereby said 25 ratchet wheel is again stepped round, and means operated by the ratchet wheel when in this position to stop the electric motor.

RAOUL FOUCES.

JACQUES LENFANT. 30
